(57) **CLAIM**

The ornamental design for a spray applicator stick as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a perspective view of the spray applicator stick showing our new design;

FIG. 2 is a left side elevational view of the spray applicator stick shown in FIG. 1;

FIG. 3 is a right side elevational view of the spray applicator stick shown in FIG. 1;

FIG. 4 is a back side elevational view of the spray applicator stick shown in FIG. 1;

FIG. 5 is a front side elevational view of the spray applicator stick shown in FIG. 1;

FIG. 6 is a top plan view of the spray applicator stick shown in FIG. 1;

FIG. 7 is a bottom plan view of the spray applicator stick shown in FIG. 1; and,

FIG. 8 is a perspective view of the spray applicator stick showing our new design with a paint gun mounted in the spray gun;

The broken lines in the Figures are directed to features that form no part of the claim.

1 Claim, 8 Drawing Sheets
